PACKER FOR CASING HEADS

Application filed June 23, 1930. Serial No. 463,218.

This invention relates to a packing device, and relates more particularly to a packer or packing assembly for use in a well casing head operable to prevent a well from blowing out through the casing.

It is a general object of the present invention to provide a simple, practical, and effective packer or packing device for use in a well casing head to pack around a drill pipe, or the like, extending through the head.

It is another object of the present invention to provide a packer for a casing head that may be easily and quickly arranged in operating position in a casing head around a drill pipe, or the like, without disturbing the pipe.

It is another object of the present invention to provide a packer for a casing head that is operable by compression to effectively pack off between the casing head and a part extending through the casing head and which may be operated either by a clamping or compressing device on or in connection with the casing head, or by the weight of a string of drill pipe, or the like.

It is another object of the present invention to provide a casing head packer of the character mentioned that embodies an expandable and compressible packing ring to seal with the casing head and to pack around a drill pipe, or the like, extending through the casing head, and which embodies novel and improved means for expanding the compressible sealing ring into effective sealing engagement with the casing head and the pipe.

Another object of this invention is to provide a packing assembly or packer of the character mentioned that is sectional or formed of units and to provide effective means for latching the sections or units together around a drill pipe, or the like.

It is a further object of this invention to provide a casing head packer of the character mentioned that embodies two split collars,

and a split expandible packing ring between the collars, that are held together or assembled by the means referred to above for expanding the packing ring.

Other objects and features of our invention will be best and more fully understood from the following detailed description of a typical form and application of the invention, throughout which description reference is had to the accompanying drawings, in which:

Fig. 1 is a vertical detailed sectional view of the packer, illustrating it in operative position in a typical casing head and packing around a drill pipe extending through the head. Fig. 2 is an enlarged longitudinal detailed sectional view of the packer. Fig. 3 is a reduced transverse detailed sectional view taken as indicated by line 3-3 on Fig. 2. Fig. 4 is a reduced transverse detailed sectional view taken as indicated by line 4-4 on Fig. 2. Fig. 5 is a reduced transverse detailed sectional view taken as indicated by line 5-5 on Fig. 2. Fig. 6 is a reduced bottom view of the packer, being a view taken as indicated by line 6-6 on Fig. 2, and Fig. 7 is a longitudinal side elevation view of the packer showing the two sections separated and the locking means about to be united.

The packer or packing assembly provided by the present invention is particularly adapted for use in comparatively large packing glands, or the like, for example, it is well suited for use in a casing head at the upper end of a well casing to prevent the well from blowing out through the casing. The invention is adapted to be embodied in packers for use in various types of well casing heads, or the like. Throughout the following disclosure we will describe the invention as embodied in a packer assembly to be used in connection with a typical well casing head H and for packing around a string of drill pipe P extending through the head H. It is to be understood, however, that the invention is not to be construed as limited for use in con-

nection with the particular type of casing head illustrated in the drawings but that it is to be taken as including any features or modifications that may fall within the scope of the claims.

The typical casing head H shown in the drawings is adapted to be applied to the upper end of a well casing and includes a body 10. The body 10 of the casing head is a vertically disposed tubular member having a central longitudinal opening 11 for passing well tools, such as the drill pipe P, and for carrying a packing device for packing off the upper end of the well casing. The body 10 of the head may be connected with the well casing in any suitable manner. In the particular case illustrated, the lower portion of the body 10 is both externally and internally screw threaded for connection with a suitable coupling, or the like, at the upper end of a well casing. The upper portion 12 of the opening 11 is intended to carry the packer for packing around the drill pipe P or the like, and is enlarged and has axial or cylindrical walls. A convergent or inwardly tapered portion 13 is provided at the lower end of the enlarged part 12 of the opening to support the packing device in the head.

The casing head H may be provided with means for compressing or actuating a packer or packing device arranged in the enlarged opening 12. The type of casing head illustrated in the drawings and more particularly the packing actuating means illustrated in connection with the casing head, is set forth in Patent No. 1,539,236, issued to M. S. Black, May 26, 1925. The particular type of casing head H illustrated in the drawings is provided with a clamping sleeve 14 at its upper end adapted to compress a packing device arranged in the opening 12. The sleeve 14 may have an inwardly extending flange 15 to engage the upper end of a split or sectional ring 17^a. The ring 17^a is adapted to be assembled or arranged in the head on the upper end of the packing. The ring 17^a has an opening 16 for passing the drill pipe P, or the like. The opening 16 is sufficiently large to pass a drill pipe coupling C to permit the coupling to engage the upper end of the packer arranged in the head as will be hereinafter described. Openings may be provided through the walls of the casing head H to receive fluid discharge conduits 17.

The packer provided by the present invention is adapted to be arranged in the opening 12 to pack off around the drill pipe P and includes, generally, an upper split collar 18, a lower split collar 19, a split annular body of packing 20 arranged between the collars 18 and 19, means 21 for expanding the packing 20 into sealing engagement with the pipe P and the walls of the opening 12 and for holding the sections of the collars 18 and 19 and the packing 20 together to form two

assemblies or units A and B, and means 22 for releasably latching the units A and B together around the pipe P.

The packing device or packer of the present invention is a laminated annular structure or assembly adapted to operate in the opening 12 of the casing head H to pack off the upper end of a well casing. The collars 18 and 19 are provided at the upper and lower ends of the expansible packing 20 and slidably fit the opening 12. The collars 18 and 19 are provided to take or receive the wear and to carry the packing 20. The lower collar 19 is provided with a tapered exterior 23 to fit in the convergent portion 13 of the casing head to support the packer in the head. Sockets or recesses 24 may be provided in the lower side of the collar 19 to lighten the construction. The upper side of the upper collar 18 is preferably made flat to receive the flange 15 of the clamping sleeve or like device, and to receive the lower end of a coupling C, or the like. Screw threaded openings 25 may be provided in the upper side of the collar 18 to receive suitable tools or devices for handling the units A and B of the packer. The collars 18 and 19 are longitudinally split at diametrically opposite points and are arranged so that their lines of division are in vertical or longitudinal alignment.

The packing 20 is in the nature of a split annular body of compressible and expansible material arranged between the collars 18 and 19. The packing 20 may be formed of rubber, rubber composition, or any other suitable expansible packing material. The body of packing 20 is longitudinally split at diametrically opposite points and is arranged so that its lines of division are in vertical alignment with the ends of the sections of the split collars 18 and 19. The packing ring 20 is proportional to slidably fit the opening 12 of the casing head to normally freely pass the drill pipe P.

The means 21 operates to connect the sections of the split collars 18 and 19 and the split packing ring 20 to form two unitary assemblies or units A and B and is such that it operates to effectively expand the packing 20 both radially inward to pack against the pipe P and radially outward to seal up the walls of the opening 12 upon a compression strain being put on the packer. Further, the means 21 operates to expand the end portions of the packing 20 of the units A and B to bring the ends of the sections of packing 20 tightly together upon the packing being compressed. It is a feature of the invention that the means 21 secures the collars 18 and 19 to the packing 20 without the use of screws, bolts, or like securing or assembling parts. The means 21 is integral with the collars 18 and 19 and includes projections 30 on the collars fitting recesses or grooves 31 in the

packing 20. A downwardly extending projection 30 is provided on the lower side of each section of the collar 18 and an upwardly extending projection 30 is provided on the upper side of each section of the lower collar 19.

The projections 30 are preferably integral with the collars 18 and 19 and are preferably curved to extend circumferentially of the collars. The projections 30 of the collars 18 and 19 are preferably directly opposite or in vertical alignment. The sides 32 of the projections 30 are tapered or outwardly convergent so that the projections 30 are in the form of wedge projections and have their greatest cross sectional dimensions at their bases. The projections 30, being formed in this manner, act as wedges to expand the packing 20 radially outward in opposite directions upon compression of the packing. Enlargements or heads 33 are provided at the outer ends of the projections 30. The heads 33 are pointed or have outwardly convergent sides to effectively spread the packing. The heads 33 present substantially horizontal shoulders 36 at opposite sides of the projections 30. The ends 37 of the projections 30 are beveled or tapered outwardly from the diametric lines of division of the units A and B so that compression of the packing 20 forces the end portions of the sections of the packing into tight compressive engagement.

The grooves 31 are shaped to conform to the configuration of the projections and heads 33 and are proportioned so that the projections may be slidably forced into the recess when the packer is assembled. The projections 33 fit tightly into the grooves 30 and the shoulders 36 prevent displacement of the projections from the grooves. The projections 30 and grooves 31 are related so that the upper and lower sides of the packing ring 20 are normally spaced from the collars 18 and 19. The grooves 31 are provided with inwardly extending reduced portions 38 at or beyond the ends of the heads 33 to permit inward movement of the heads 33 without danger of fracturing or cracking the packing. Upon a compression string being put on the packer either through the sleeve 14 or like device, or through the weight of the string of pipe P being put on the packer, the projections 30 of the upper collars 18 are forced downwardly in the grooves 31 and the packing 20 is forced downwardly on the upwardly extending projections 30 of the lower ring 19 so that the packing is expanded radially inward by the projections 30 against the pipe P and radially outward against the walls of the opening 12.

Compression of the packing 20 causes the tapered ends 37 of the projections to compress the end portions of the sections of

packing together to provide an effective seal between the sections of the packing.

The means 22 for latching the assembly or units A and B together around the pipe P is such that the units A and B may be quickly and easily arranged in operative position around the drill pipe before being lowered into the casing head H. The means 22 is preferably in the form of a latch means and is preferably integral with the collars 18 and 19. In the form of the invention illustrated in the drawings, the means 22 includes latch projections 40 on the unit A to cooperate with latch catches or lugs 41 on the collar of the unit B. The latch projections 40 project from the opposite ends of the sections of the collars 18 and 19 of the unit A. The latch projections 40 are provided with pointed or convergent ends having tapered faces 42 terminating in vertical shoulders 43. The lugs 41 are provided at the inner sides or bottoms of the recesses 44 in the end portions of the sections of the collars 18 and 19 of the units B. The lugs 41 are provided with tapered faces 46 to receive or cooperate with the tapered faces 42 of the projections 40 and have shoulders 47 to cooperate with the shoulders 43. The projections 40 and the lugs 41 are proportioned and related so that the units A and B may be forcibly sprung together to cause the beveled faces 42 of the projections to ride over the tapered faces 46 of the lugs so that the shoulders 43 and 47 are brought into cooperative engagement. In practice the latch projections 40 of the lower collar 19 may be arranged in cooperative engagement with the lugs 41 of the lower collars and the units A and B swung together to force the projections 40 and the lugs 41 of the upper collar 19 into cooperative position. When the units A and B are arranged together to latch the means 22, the packing 20 of the unit A is stretched or elongated longitudinally and the packing 20 of the unit B is compressed to allow the shoulders 43 and 47 to come into cooperative engagement. The inherent resilience of the packing 20 releasably retains the latch projections 40 in cooperative engagement with the lugs 41.

The packing 20 yieldingly holds the collars 18 and 19 spaced apart in a position where the latch projections 40 are positively held in latching engagement with the lugs 41. The projections 40 may be released from the lugs only by acting on the packing 20. When a heavy blow is imparted to the outer edge of either of the collar sections of the unit A the outer portion of the packing 20 of the unit A is compressed and the inner portions of the packing 20 is stretched and the latch projections of that collar section are moved vertically and released from the lugs. The latch means may be released by compressing the packing 20 of the unit B to shift the lugs

41 of one collar section out of engagement with the projections 41.

It is believed that the utility and practicability of the packer provided by the present invention will be readily apparent from the foregoing detailed description. In employing the device the units A and B may be assembled around a pipe P or the like in the manner described above and lowered into the opening 12 of the casing head. The beveled exterior 23 of the lower collar 19 rests against the convergent portion 13 of opening 12 to support the packer in the head. When it is desired to operate the packer to seal off around the pipe P or the like, the compression sleeve 14, or like device on the head H may be operated to compress the packing 20. If desired the weight of the drill pipe P may be employed to compress the packing by permitting the coupling C to support the weight of the drill pipe on the collar 18. A compression strain put on the packer in any manner causes the projections 30 to be forced into the packing 20 to expand the packing radially in opposite directions as well as circumferentially to tightly seal with the walls of the opening 12 and the pipe P.

The packing assembly provided by the present invention is particularly easy to arrange in operative position in the casing head, or the like, and embodies but few simple parts. The units A and B may be disconnected or separated by imparting a blow to either the section of the collar 18 or section of the collar 19 of the unit A to permit the latch projections 40 to spread out of engagement with the lugs 41. In practice the packer may be dropped so that a blow is struck on a corner of the section of the lower collar 19 of the unit A to compress the outer portion of the packing 20 of the unit A to allow the latch projections to spring out of engagement with the lugs. The projections 30 operate to retain the collars 18 and 19 and the packing 20 assembled as well as to effectively expand the packing upon compression of the packer.

Having described only a typical preferred form of our invention, we do not wish to limit ourselves to the specific details set forth, but wish to reserve to ourselves any changes or variations that may appear to those skilled in the art or fall within the scope of the following claims.

Having described our invention, we claim:

1. A packing device of the character described including expansible packing, collars at the ends of the packing, and means for expanding the packing and for holding the packing and collars assembled including wedge parts on the collars extending into the packing, and enlargements on the wedge parts.

2. A packing device of the character described including, a collar, expansible pack-

ing, means for expanding the packing including a part on the collar having a tapering side and extending into the packing, and a projection on the said part holding the collar and packing assembled together.

3. A packing device of the character described including, expansible resilient packing, collars at opposite ends of the packing, means for expanding the packing radially including parts on the collars having longitudinally tapered sides and extending into the packing, and means for holding the packing and collars assembled including lateral projections on the said parts.

4. An annular packing assembly including collars, and resilient packing between the collars, the assembly being longitudinally split into separable units, and means for releasably holding the units together through the resiliency of the packing.

5. An annular packing assembly including collars, and resilient packing between the collars, the assembly being longitudinally split into separable units, and means for releasably holding the units together, including a lug on one unit, and a latch projection on the other unit, the latch and lug being releasably held in cooperative engagement by the resiliency of the packing.

6. A substantially annular packing assembly including collars, and yieldable resilient packing between the collars, the assembly being longitudinally split into separable units and means for releasably holding the units together including cooperating parts on the collars, the packing yieldingly holding the collars spaced apart in a position where the parts are in cooperative engagement.

7. A packing device including a yieldable resilient packing ring, collars at the opposite ends of the packing ring, the assembly of the collars and ring being longitudinally split into separable units, and means for releasably holding the units together including a lug on a section of a collar of one unit, and a projection on a section of a collar of the other unit cooperating with the lug, the lug and projection being releasable by acting on the packing.

8. A packing device including a packing ring, collars at the ends of the ring, and means for expanding the packing radially upon a compression strain being put on the device including a wedge projection on a collar extending into the packing, the assembly of the packing ring and collars being longitudinally divided into separable sections, the end of the wedge projection being adjacent a line of division of the assembly and being tapered to cause circumferential expansion of the packing.

9. A packing device including a yieldable resilient packing ring, collars at the ends of the ring, means for expanding the packing including a wedge part extending into the

packing, the assembly of the packing ring and the collars being longitudinally divided into separable units, and means for releasably holding the units together including cooperating parts on the collars adjacent a line of division of a collar releasably held in cooperative engagement through the resiliency of the packing ring.

5 In witness that we claim the foregoing we have hereunto subscribed our names this 16th
10 day of June, 1930.
